UNITED STATES PATENT OFFICE

FRED L. WAGAR, OF WAGAR, ALABAMA

TRUNK AND BOX

Application filed May 29, 1929. Serial No. 366,887.

The object of the invention is the production of a trunk, box, chest or other like casing which shall be of great strength, light in weight, very durable, and relatively cheap

5 to manufacture, considering the desirable qualities appertaining to, possessed by, or characteristic of the same.

The invention consists in a casing, preferably provided with a cover, or of two casings matching or hinged together and constituting a trunk, box or chest, the main part or parts or walls of which are comprised of corrugated sheets of metal, two sheets of corrugated metal in most instances 10 being used, the corrugations of one sheet being at angles, preferably right angles, to the corrugations of the other sheet, and the sheets united at their points or areas of contact by welding, electrically or otherwise, or by mechanical means, as rivets.

15 The invention further consists in such a casing, trunk, box or chest with an exterior metallic covering and an interior lining, either or both.

20 The accompanying drawings illustrate two examples of the embodiment of the invention, one wherein the casing, trunk or box consists of two parts similarly constructed and matching or hinged together, and the other of a casing provided with a lid or cover, the same being constructed and the parts combined according to the best modes of procedure I have so far devised for the purpose.

25 Figure 1 is a cross section of a trunk or casing comprised of two similarly constructed parts matching and united at two of their meeting edges by a hinge.

30 Figure 2 is a full horizontal sectional plan view of the device shown by Figure 1 taken on line 2—2.

35 Figure 3 is a perspective view of the outer corrugated part or element of half the trunk or box.

40 Figure 4 is a perspective view of the inner corrugated part or element of half of the trunk or box.

45 Figure 5 is a perspective view of the structure produced by placing the inner part

Figure 4 within the outer part Figure 3 and uniting them by welding or other means.

Figure 6 is a perspective view of an inner lining.

55 Figure 7 illustrates the blank for forming the inner lining.

Figure 8 is a perspective view of the structure formed by placing the said inner lining Figure 6 within the structure shown by Figure 5.

60 Figure 9 is a perspective view of the outer covering for one of the halves of the trunk or box.

65 Figure 10 is a perspective view of the structure formed by applying the outer covering Figure 9 to the structure shown by Figure 8.

70 Figure 11 is a sectional view much enlarged of one of the corners of Figure 10.

Figure 12 is an enlarged vertical sectional view through the meeting edges of the two halves of the trunk or box illustrated by Figure 1, showing the hinge.

75 Figure 13 is an enlarged vertical sectional view, showing the meeting edges of the two parts or halves opposite the hinged edges.

Figure 14 shows a clamping device.

80 Figure 15 is a cross sectional view of the second example having a hinged lid.

85 As each part of half of the trunk or box shown by Figure 1 is of substantially the same construction, the specific construction of one half only is sufficient.

Referring in particular to Figures 3 to 11, inclusive, A designates the outer box-shaped part or elements made of corrugated metal, the sides and bottom having longitudinal corrugations and the ends vertical corrugations, Figure 3. B is the inner box-shaped part or element made of corrugated metal, the ends and bottom having cross corrugations and the sides vertical corrugations, Figure 4.

90 When box B is placed in box A their union will produce the structure shown by Figure 5 wherein the corrugations of two sheets in any plane are at right angles. The two boxes, when disposed as shown in Figure 5, are welded together at their points or areas of contact as designated at 1 in Figure

95 11. A and B may be fashioned from blank 100

sheets of corrugated metal, the same being cut to shape and the edges bent up and the meeting edges or corners united by welding. The inner lining C, Figure 6, is fashioned 5 from a blank piece of metal shown by Figure 7, the same being cut to shape and the edges turned up and welded together at the corners. One longitudinal edge 2 is fashioned to form a series of eyes 3 which match 10 with similar eyes at the corresponding edge of the other half of the trunk or box, and a rod 4 being passed through alternate eyes forms a hinge as shown by Figure 12.

The inner lining is placed within the 15 structure shown by Figure 5 and secured to the inner corrugated part B by welding or otherwise, forming the structure shown by Figure 8.

The outer metallic covering D, Figure 9, 20 is made from a blank, such as shown by Figure 7, but without the eyes. The structure shown by Figure 8 is placed within the casing D and the covering united to the part A by welding at the corners or at other 25 points or areas, thus forming the structure shown by Figure 10.

To insure the matching and interlocking 30 of the edges of the two halves of the trunk or box, shown by Figure 1, when united, the edges of the corrugated sheets B, B are beveled at 5, Figures 12 and 13, the edges of the inner linings C, C being extended over the beveled edges, Figure 12, and terminating in the eyes 3, forming with the rod 35 4 a hinge.

Any suitable locking or clamping means 40 may be used at the side opposite the hinge for holding the two parts or halves together. A conventional form of clamping means is shown by Figures 13 and 14, where a pivoted rotary disk with a hook on one of the halves of the trunk is adapted to engage the shank of a headed stud on the other half.

Figure 15 illustrates the second example 45 of the embodiment of the invention in which the box part is constructed as previously described. The lid 6 is comprised of two sheets of corrugated metal, the corrugations of one sheet disposed at right angles to the corrugations of the other sheet, and the sheets united or welded together at their points or areas of contact. Outer and inner plain sheets of metal are welded or secured to the opposite surfaces of the sheets of corrugated metal and a hinge 7 is formed at 50 the meeting edges of the box and lid substantially as hereinbefore described for the first example.

From the foregoing description and illustrations it will be clear that I have invented 60 a novel casing, such as a trunk, box, or chest, which is of great strength, light in weight, very durable, and relatively cheap in first cost in view of its desirable characteristics and qualities. The invention may,

of course, be embodied by other modes of procedure and in other forms than the two examples specifically described, and the relative dimensions of the parts be changed 70 without a substantial departure from the principle of the invention.

What I claim is:

1. A casing, such as a box, trunk or chest, having the main body part thereof comprised of two sheets of corrugated metal, 75 the corrugations of one sheet disposed at angles to the corrugations of the other sheet and the said sheets united at their points or areas of contact.

2. The subject-matter of claim 1 wherein the said main body part is provided with an exterior metallic covering secured to the main body part. 80

3. The subject-matter of claim 1 wherein the said main body part is provided with 85 an inner lining.

4. The subject-matter of claim 1 wherein the said main body part is provided with an inner lining and outer covering, and a lid or cover comprising two sheets of corrugated metal, the corrugations of one sheet disposed at angles to the corrugations of the other sheet, and the sheets united at their points or areas of contact. 90

5. A casing, such as a trunk or box, having two parts matching each other, each part comprising two sheets of corrugated metal, the corrugations of one sheet disposed at angles to the corrugations of the other sheet, and the sheets united at their points or areas 100 of contact.

6. The subject-matter of claim 5 wherein each of said parts is provided with an inner lining and an outer covering. 105

7. The subject-matter of claim 5 wherein said two parts are provided with a hinge at one of their adjacent meeting edges. 110

In testimony whereof I affix my signature.

FRED L. WAGAR.
